LOOP ANTENNA CONSTRUCTION

Trevor H. Clark, New York, and Philip J. Vander Woude, Riverdale, N. Y., assignors to Federal Telephone and Radio Corporation, Newark, N. J., a corporation of Delaware

Application March 5, 1943, Serial No. 478,082

12 Claims. (Cl. 250—33)

1

This invention relates to improvements in loop antenna construction, and more particularly to a short-wave crossed loop wave collector adapted for installation on board ships, especially on top of masts.

An object of this invention is to provide a novel improved antenna assembly including crossed loops, sense antenna, and counterpoise, which is especially adapted for use in connection with direction finding systems aboard ships.

Another object of this invention is to provide an antenna assembly of the type described which can readily be mounted upon the usual ship mast structures.

A further object of this invention is the provision of a novel hollow water-proof base member for receiving the ends of the loops in an antenna assembly which may include crossed loops, sense antenna and counterpoise.

An additional object of this invention is directed to providing a novel hollow supporting base for an antenna assembly in which terminal blocks are mounted in and about the hollow base.

Still another object of our invention is the provision of a hollow base mounting for a loop antenna formed of flexible shielded cables.

With the foregoing and other objects in view which will appear as the description proceeds, the invention resides in the combination and arrangement of parts and in the details of construction hereinafter described and claimed.

The invention has been illustrated in its preferred embodiment in the accompanying drawings wherein:

Fig. 1 is a vertical view example of an antenna assembly which may be used with the present invention;

Fig. 2 is a top plan view of the general antenna assembly illustrated in Fig. 1;

Fig. 3 is an enlarged cross-sectional view of a novel base for the antenna assembly in accordance with the present invention;

Fig. 4 is a plan view of a terminal block used in the base shown in Fig. 3;

Fig. 5 is a cross-sectional view of the terminal block taken along the line 5—5 of Fig. 4;

Fig. 6 is a cross sectional view of a cable holding device taken along the line 6—6 of Fig. 3.

The general antenna assembly will be readily apparent from a study of Figs. 1 and 2. Primarily, it includes a generally vertical supporting rod 10 from the vertical mid-point of which extend four radial arms 12 spaced 90° relatively to one another and attached to the rod 10 by means of a suitable connector 13. The bottom of the supporting rod

2

10 is held in a strengthening support 14 which, in turn, is mounted upon a generally hemispherical base member 16. The latter, in turn, may be attached to the top of a ship mast indicated at 17. The four arms 12 may be interconnected by bracing bars 20 attached thereto by suitable clamping devices 22.

The crossed loop may be formed by two flexible shielded cables 24 and 26, the apices of which pass through a top mount 18 attached to the top of a supporting rod 10, the ends of which are fastened within the base member 16 and the central portions of which are held by fastening devices 28 on the ends of the respective arms 12. Above the top mount 18 may be fixed an insulating ring 29 which supports a metal cap 30 from which projects a plurality of counterpoise rods 32. These rods are positioned at 90° relatively to one another. A sense antenna 34 extends vertically upwardly from an insulating disk 36 mounted on top of the cap 30. The particular manner of mounting the sense antenna, counterpoise rods, the connection between these two and the attachment of the crossed loop to the top mount 18 is all more fully described in the copending application of T. H. Clark, S. N. 478,081, filed March 5, 1943.

In Fig. 3 we have shown details of the novel hollow base member of the present invention, 30 upon which the antenna system is mounted. This will consist of a generally hemispherical hollow casting 16 which will rest upon a suitable flange 138 on the top of the mast 17. A watertight gasket 139 is interposed between the casting 16 and the flange 138 and rigid connection may be made through means such as bolts 141. The supporting rod 10 is held within the supporting base frame 14, the latter being attached to the top of the base casting 16 as through bolts 140. A sealing gasket 142 is preferably interposed. The sloping sides of the casting 16 are formed with four spaced openings 144 to receive the ends of the loops 24 and 26. These loop ends must be rigidly attached to the base 16 to give rigidity 45 to the loops and the connection must be watertight. To effect such an arrangement the openings 144 are provided on the outside with a circular internally threaded portion adapted to receive a collar 150 externally threaded at both ends. One end of the collar 150 is threaded into the openings 144 and presses against a grounding washer 148 which, in turn, presses against the end of a ferrule 146 brazed or otherwise attached to the braided shield 78 on the cable 24. Within 50 the collar 150 is positioned a rubber sleeve 152

which tightly grips the surface of the cable and is pressed against the cable and externally against the collar 150 by means of a compression nut 154 threaded over the other end of the collar. This arrangement holds the cables tightly with respect to the base 16, but leaves the extremities of the loops free of strain so that they may be readily connected to appropriate terminal blocks. Similar holding means are, of course, used to hold the lower ends of loop 26.

These terminal blocks are positioned around the bottom of the base 16 and are mounted in suitable openings therein. For the ends of the loops we have provided terminal blocks 156 which are attached to the base 16 by means such as screws 158 and 160 on the inner side of the terminal blocks 156, and held in place by the nuts upon the screws 158 are clamps 162 which surround the shielded ends of the cable and rigidly hold them to the terminal block. Leads 164 extend from each screw 158 to a common central rod 166 passing from one side of the terminal block to the other. A lead 168 on the outside of the terminal block connects the pin 166 to the shield 170 of a flexible dual cable 172 extending down and externally of the mast 17 to the radio equipment. The terminal blocks 156 are also provided with a pair of through pins 174 to which are attached the ends of the loop conductors themselves. As will become clear from a study of Figs. 4 and 5 in connection with Fig. 3, between the pins 174 and a second pair of pins 178 positioned immediately below them are attached resistors 176 for the purpose of improving the characteristics of the loop antenna, as more clearly explained in the copending application of Daubaras, S. N. 478,079, filed March 5, 1943. The lower pins 178 are, in turn, attached through leads 180 to the dual wires of the cable 172. The various pins 156, 174 and 178 are held in place in the terminal blocks by enlarged fluted portions 167.

The dual cables 172 forming the transmission line to the radio apparatus are held within the base 16 by means of rubber bushings 186 pressed about the end thereof and mounted on one side in a cut-out section 184 of each terminal block and held on the outside by a cover 190 which is attached about the openings in the base 16 as by bolts 194. These covers at the same time serve to protect the exposed sides of the terminal blocks and in order to provide a water-tight connection, suitable gaskets 194 may be interposed between each cover and the base.

The terminal block 156' serves for a dual cable 92 which may extend a dummy loop network (not shown) interconnecting the sense antenna and counterpoise, downwardly through the hollow supporting rod 10, is similar in construction to the terminal blocks 156 but does not include the clamps 162, the pins 174 and the resistors 176. Instead, an inner shield of the cable 92 is directly connected to the central pin 166' while the two wires from the dual cable are respectively directly connected to the lower pins 178'. The pins 166' and 178' extend through the terminal block 156' and are connected with the dual cable 172' in a manner identical with that described in connection with the terminal blocks 156 and the dual cables 172.

In order to hold the dual cable 92 in place we have provided, as is more clearly indicated in Fig. 6, a clamp 197 attached to the underside of the base 16 by screws 198 in the vicinity of the opening for one end of the cable 24, this clamp

being crimped about the lower end of the dual cable.

While we have described the principles of our invention in connection with certain specific structure, it is to be clearly understood that this description is made only by way of example and not as a limitation on the scope of our invention as set forth in the objects and the accompanying claims.

10 We claim:

1. A wave collector including, in combination, a hollow base member in the form of a generally hemispherical metal shell open at the top and provided with at least three angularly spaced openings at its side, a terminal block mounted in each of said openings, a hollow supporting rod positioned on and communicating with said base member through the opening in the top thereof, a top mount, supported on the top of said supporting rod, four arms positioned at right angles to one another and extending radially outwardly from substantially the vertical midpoint of said supporting rod, a loop antenna comprising two loops, each loop having its closed top fixed in said top mount and its ends fixed in said base member, one loop being supported by two opposite arms and the other member being supported by the other two opposite arms, whereby the two loops are positioned at 90° relatively to one another, a vertical sense antenna supported from said top mount, a counterpoise attached to said top mount, said counterpoise comprising four radially directed rods extending from said top mount at right angles to one another, a transmission line connected to said sense antenna and counterpoise, said transmission line including a dual cable extending from said hollow top mount through said hollow supporting rod into said base member, and means for connecting the ends of one loop to a first terminal block, the ends of the other loop to a second terminal block, and the lower ends of said dual cable to the third terminal block.

2. The combination according to claim 1, in which each of said loops is formed of a shielded insulated flexible cable, in combination with grounded clamping means on said first and second terminal blocks, respectively engaging the shield on said loops.

3. The combination according to claim 1, in combination with clamping means attached to the inside of said base member and engaging said dual cable.

4. The combination according to claim 1, in which each of said terminal blocks is provided with terminal pins extending therethrough and the ends of the loops and the ends of the dual cable are electrically connected to those terminal pins on the inside of the hollow base member, in combination with lead-out cables attached to the outer ends of the pins, and covers attached to said base member respectively enclosing the outer ends of the pins of each terminal block.

5. The combination according to claim 1, in which each terminal block is provided on the outside with an inwardly directed cut-out near its lower end and with terminal pins extending therethrough, and the ends of the loops and the ends of the dual cable are electrically connected to those terminal pins on the inside of the hollow base member, in combination with lead-out cables respectively attached to the outer ends of the pins, lead-out cable fastening means positioned in each of said cut-outs, and covers attached to said base member respectively enclosing the outer

ends of the pins of each terminal block and holding said cable fastening means in said cut-outs.

6. The combination according to claim 1, in which said base member is formed with openings in its shell to receive the ends of the loops, in combination with means in said openings grasping the loop passing therethrough and tightly attaching the same to the base member.

7. The combination according to claim 1, in which said base member is formed with openings in its shell to receive the ends of said loops, in combination with means in said openings forming a water-tight joint about the portions of the loop passing therethrough, and a water-tight covering attached on the outside of said shell about the outer side of each terminal block.

8. The combination according to claim 1, in combination with a strengthening support surrounding the lower end of said hollow supporting rod, and water-tight means for mounting said strengthening support on said base member.

9. A wave collector, including in combination, a hollow base member in the form of a generally hemispherical metal shell having at least three openings in its side, a terminal block mounted in one of said openings, a vertical supporting rod mounted on said hollow base member, a loop antenna attached to said supporting rod and having its lower end passing into said base member through the other openings therein, water-tight means firmly holding the loops in said two openings, a water-tight cover attached to said base member about the terminal

block in the other opening, and means for electrically connecting the lower ends of the loop to said terminal block.

10. The combination according to claim 9, in which said loop is formed of a shielded flexible cable, in combination with grounded clamping means on said terminal block engaging the shields on the ends of the loop.

11. The combination according to claim 9, in which said terminal block is provided with terminal pins extending therethrough and the ends of said loops are connected to those pins on the inside of said base member, in combination with a lead-out cable positioned on the outside of said terminal block and within the terminal block cover attached to the outer ends of said pins.

12. The combination according to claim 9, in which each terminal block is provided on the outside with an inwardly directed cut-out near its lower end and with terminal pins extending therethrough, and the ends of the loops and the ends of the dual cable are electrically connected to those terminal pins on the inside of the hollow base member, in combination with lead-out cables respectively attached to the outer ends of the pins, lead-out cables fastening means positioned in each of said cut-outs, and covers attached to said base member respectively enclosing the outer ends of the pins of each terminal block and holding said cable fastening means in said cut-outs.

TREVOR H. CLARK.
PHILIP J. VANDER WOUDE.
